UNITED STATES PATENT OFFICE.

CHARLES HENRI CLAUDEL, OF LEVALLOIS PERRET, FRANCE.

EXPLOSION-MOTOR.

1,307,185.

Specification of Letters Patent. Patented June 17, 1919.

Application filed November 14, 1917. Serial No. 202,021.

To all whom it may concern:

Be it known that I, CHARLES HENRI CLAUDEL, citizen of the Republic of France, residing at 41 Rue des Arts, Levallois Perret, 5 Seine, in the Republic of France, have invented new and useful Improvements in Explosion-Motors, of which the following is a specification.

This invention relates to improvements in 10 explosion motors.

When an explosion motor is fed by means whereby reduced speeds are obtained by reducing the amount of mixture admitted lowering of the compression results which causes 15 a fall in the power which becomes greater as the motor runs slower.

When such a motor is fed with heavy fuels it generally happens that difficulty is found in obtaining regular running at slow 20 speed.

The present invention comprises means whereby when the admission of the gases is reduced by operating a throttle or similar member the apparent compression in the 25 combustion chamber increases or in any case diminishes less rapidly than usual.

In the annexed drawing, is represented by way of example a form of construction of the invention:—

30 Figure 1 is a diagrammatic view of an example of the application of the invention to a four stroke motor.

Figs. 2 and 3 are diagrams showing the variation of regulation which can be obtained.

Referring to Fig. 1 it can be seen that the admission valve 1 is connected to the carbureter or vaporizer 3 by means of a tube 10 in which is arranged a throttle valve 2 for 40 regulating the speed of the motor.

The throttle valve 2 is operated by means of a controlling lever 15 keyed on a shaft 16 carrying a lever 13 which may actuate an arm 17 secured on the axis of the throttle 45 valve. To the lever 15, is also connected a short connecting rod 18 and, fulcrumed on the end of the latter, is a wedge shaped pawl 4 which is placed between the cam 5 actuating the admission valve 1 and the valve stem.

50 The wedge or pawl 4 has an inclined bottom face 4^a which is acted upon by the boss 5^a of the cam and a reversely sloped projection 4^b which rests upon a circular boss or hub of the cam when the wedge is not lifted by

said cam. The part 4^b has for its purpose 55 to reduce the extent of the oscillating movement of the wedge about its axis and reduce the noise.

When the lever 15 is swung in the direction of the arrow to run at slow speed, the 60 wedge 4 is advanced under the valve stem and the face 4^a of the wedge being inclined as shown, the boss 5^a of the cam will leave said face sooner whereby the admission valve will be closed sooner than in normal 65 operation. If for instance in normal running the admission valve was open while the crank shaft pin is traversing the arc F E (Fig. 2), the arrangement may be such that the admission be cut off, at slow speed, for 70 instance at point e near the lower dead point B, the opening of admission then taking place at f. In normal running, when the crank pin traverses the arc B E, the piston forces the fresh gases back into the feeding 75 pipe 10, which is objectionable and compression is effected over the arc E A only while in slow speed running, owing to the arrangement described, the compression is effected for instance over the whole arc e A 80 i. e. is practically maximum. The working at slow speed is thus facilitated and improved.

The lever 13 can also be connected as shown by a connecting rod 12 to a lever 19 85 similar to lever 13 which is pivoted at 20 and connected by a connecting rod 21 to a wedge member 7 similar to wedge 4 and interposed between the stem of the exhaust valve 6 and its actuating cam 8. The bottom face 7^a of wedge 7, which co-operates with the cam is inclined in the same direction as the face 4^a of the wedge 4 so that when the lever 15 is operated to run at slow speed, the wedge 7 is advanced under the 90 stem of the valve 6 and the boss 8^a of the cam 8 leaves the face 7^a sooner whereby the exhaust valve is closed sooner than in normal running. If, for instance, in normal operation, the exhaust valve was opened in 95 the period A¹ B¹ (Fig. 3), the arrangement described may be so constructed that the said valve be closed at H¹ or even at D¹, the opening taking place at G¹ or C¹, respectively. By means of the advanced closure of the exhaust valve, the exhaust gases are partially retained in the working cylinder whereby the cylinder at the end of the 100 105

following aspiration stroke is filled more completely and the next compression operation is improved.

The operation of the motor could also be improved by a throttle 9 mounted in the outlet pipe 11 for the exhaust gases and connected, for instance to an extension 19^a of the lever 19 through an arm 22, or operated independently but in such a way that when the 10 admission is reduced the sectional area of the passage for the evacuation of the burnt gases will also be reduced. In the latter case it will be advantageous to place the gas throttle beyond the heating conduit 14 of the car- 15 bureter in order that during running at slow speed the heating will be the maximum.

It is understood that the devices described above and shown in the drawing are given by way of example and that without departing 20 from the invention the arrangement of the various members of the operating mechanism can be modified as may be required.

Having now described my invention, what I claim as new and desire to secure by Letters Patent is:

1. In an explosion motor, the combination of: a cylinder, a suction pipe, means for feeding an explosive gaseous mixture to said suction pipe, a throttle valve mounted in this suction pipe and adapted to control the delivery of the explosive mixture, an admission valve, a cam operating this admission valve, means controlling the aforementioned throttle valve, means arranged between the said cam and the rod of the admission valve and regulating the lifting of this admission valve, and means connecting the said regulating means to the controlling means of the throttle valve, substantially as described and 40 for the purpose set forth.

2. In an explosion motor, the combination of: a cylinder, a suction pipe, a throttle valve mounted in this suction pipe, an admission valve, a cam operating this admission valve, means controlling the aforementioned throttle valve, means arranged between the said cam and the rod of the admission valve and regulating the lifting of this admission valve, 50 means connecting the said regulating means to the controlling means of the throttle valve, an outlet valve, a cam operating this outlet valve, means arranged between this cam and the rod of the outlet valve and regulating the lifting of this outlet valve, and means connecting the said regulating

means to the controlling means of the throttle valve; substantially as described and for the purpose set forth.

3. In an explosion motor, the combination 60 of: a cylinder, a suction pipe, a throttle valve mounted in this suction pipe, an admission valve, a cam operating this admission valve, means controlling the aforementioned throttle valve, means arranged between the said cam and the rod of the admission valve and regulating the lifting of this admission valve, means connecting the said regulating means to the controlling means of the throttle valve, an outlet valve, 70 a cam operating this outlet valve, means arranged between this cam and the rod of the outlet valve and regulating the lifting of this outlet valve, means connecting the said regulating means to the controlling means 75 of the throttle valve, an exhaust pipe, a throttle valve mounted in the said exhaust pipe, means operating this throttle valve, and means connecting the said operating means to the controlling means of the 80 throttle valve mounted in the suction pipe, substantially as described and for the purpose set forth.

4. In an explosion motor, the combination of: a cylinder, a suction pipe, a throttle valve mounted in this suction pipe, an admission valve, a cam operating this admission valve, a lever controlling the aforementioned throttle valve, a pawl arranged between the said cam and the rod of the admission valve, a lever connecting this pawl to the lever controlling the throttle valve, 90 an outlet valve, a cam operating this outlet valve, a pawl arranged between the said cam and the rod of the outlet valve, an exhaust 95 pipe, a throttle valve mounted in the said exhaust pipe, a lever operating this throttle valve, a lever connected to the pawl of the outlet valve, and to the said operating lever, and an actuating rod connected to the operating lever of the second throttling valve 100 and to the controlling lever of the first throttling valve, substantially as described and for the purpose set forth.

In testimony whereof I have signed my 105 name to this specification in the presence of two subscribing witnesses.

CHARLES HENRI CLAUDEL.
